VARIABLE-SPEED TOP

Carl J. Green, Oak Ridge, Tenn.

Application March 14, 1951, Serial No. 215,437

4 Claims. (Cl. 46—49)

1

This invention relates to spinning tops and particularly to tops with variable surface coloration and/or tone.

The principal object of the present invention is to provide a synchronous variation in the speed of the spinning top during acceleration and deceleration.

Another object of the invention is to provide a top which will rise from a position of rest on its outer shell, which will accelerate, decelerate, and return to rest during the spinning cycle.

Still another object of the invention is to utilize the spinning motion of the top to induce changes in and to modulate the speed of rotation of the top.

A further object of the invention is to simultaneously induce rotation and angular velocity modulation in the top.

Other objects of the invention include the utilization of changes in angular velocity of the top to induce changes in the appearance of the surface coloration and/or changes in tone or tones produced during the spinning of the top.

In my application for Letters Patent, Serial Number 196,466, filed November 18, 1950, I disclosed a spinning top comprising the combination of an outer shell consisting of upper and lower hollow cup shaped members, said members being secured together at their peripheral edges, means within said outer shell for rotating the top, rotatable members engaged with the rotating means and balanced in respect to the axis of the top, a counterpoise near the periphery of each rotatable member, and an inertia member engaged with the rotating means and rotatable about the axis of the top. The rotatable members were in a plane perpendicular to the axis of the top.

In the present invention the rotatable members are in a plane coincident with the axis of the top.

In the accompanying drawings which form a part of the specification and wherein reference symbols refer to like parts wherever they occur,

Fig. 1 is a vertical, sectional view of one embodiment of the present invention, and

Fig. 2 is a sectional view taken substantially along line 2—2 of Fig. 1.

In Fig. 1 and Fig. 2, the outer shell of the top consists of upper and lower cup shaped members 10 and 12, respectively, secured together at their abutting peripheral edges 14. The spring motor 16 is secured to the upper shell member 10 by brackets 18 and directly connected with axial shaft 20. The knob 22 engages the end of shaft 20 during the winding of motor 16. Withdrawing pressure from knob 22 operates release 24 and starts the action of wound motor 16.

Worm gear 26, an integral part of axial shaft 20, engages gears 28 and 30 which are located in a plane coincident with axial shaft 20 and bal-

2

anced in respect to the axis of the top. Counterpoises 32 and 34 are attached to or made an integral part of gears 28 and 30, respectively. Gears 28 and 30 are held in position by support 36 attached to the upper shell member 10 by brackets 38. Inertia member 40 is energized by motor 16 through direct attachment to shaft 20.

The exterior of the outer shell members 10 and 12 are pigmented in areas indicated schematically by 42 and 44 for producing apparent color changes during the spinning of the top. Apertures in the lower shell member 12 represented by apertures 46 are provided for sound production during the spinning of the top.

In the operation of the top shown in Fig. 1 and Fig. 2 the spring motor 16 is wound by knob 22 while the latter is depressed to engage the end of axial shaft 20. The engagement of release 24 continues during winding and thereafter the raising of knob 22 disengages the release 24 and starts the operation of motor 16. The top is placed on its side so that it rests on lower shell 12. As motor 16 starts, shaft 20, gears 28 and 30, and inertia member 40 start to rotate. However, since the axial shaft 20 is not connected to either of the shell members 10 and 12, the shell of the top does not move appreciably until the acceleration of inertia member 40 is sufficient to cause the axis of the top through shaft 20 to assume a substantially vertical position.

As the axis of the top assumes such substantially vertical position, the reaction of motor 16 on upper shell member 10 to which it is attached by bracket 18 is such as to cause the outer shell of the top to revolve in the direction opposite to the direction of revolution of inertia member 40. The average speed of rotation of the outer shell of the top will approximate that of the speed of rotation of inertia member 40.

Upon acceleration of the outer shell of the top to the speed for tone production and the critical speed for color change, the effect of the operation of counterpoises 32 and 34 is such as to produce continuous rhythmic undulation in the speed of rotation of the shell which results in corresponding changes in tone and color from apertures 46 and pigmented areas 42 and 44, respectively.

The shell of the top may be of any suitable configuration such as upper and lower hollow cup shaped members secured together at their abutting peripheral edges.

The exterior of the shell may be pigmented in whole or in part so that movement of the pigmented areas above a critical speed will result in the optical effect of producing colors other than that of the pigments used. Conversely, the original colors will seem to reappear as the speed

of any zone on the exterior of the top falls below the critical speed.

The top may be provided with conventional tone producing means, such as a series of apertures or a series of apertures with reeds associated therewith.

Although both the tone producing means and the use of pigmentation are conventional, the combination with the present variable speed top provides for the production of variable tones and colorations during the synchronous acceleration and deceleration of shell speed.

As with any spinning top, the overall performance during any one complete cycle of operation consists of a general acceleration until a maximum peripheral speed is reached followed by a general deceleration until the top stops spinning. However, in the present invention, there is a rhythmic undulation in the peripheral speed of the top throughout the periods of general acceleration and deceleration with a corresponding rhythmic change in color and/or tone.

As the spiral gear, which is an integral part of the axial shaft, drives the rotatable gear members, the counterpoises on such members move toward the periphery of the top and then move toward its axis wherein the shaft is located, and so on through the complete spinning cycle. Thus, there is a series of short periods of rhythmic acceleration and deceleration corresponding to the time for the counterpoises to make one revolution about the axis of the respective rotatable gear members.

As the pigmented areas on the shell of the top move to the critical speed, the colors blend and unblend as the areas move just above and just below such speed during the short periods of rhythmic acceleration and deceleration. These color changes will then move successively from the periphery toward the center of the shell of the top during the period of general acceleration and the reverse during general deceleration. A centrifugal governor device may be engaged with the axial shaft in order to arrest the acceleration to the desired extent and to maintain the rhythmic undulations with a substantially constant average speed of the rotating shell.

Any suitable means may be used to supply the energy or means for transmission of energy to actuate the top, such as a spring wound motor. In any event the power is applied to an axial shaft and a worm gear which may be an integral part of the shaft. The worm gear engages two rotatable gear members which are in a plane coincident with the axis of the top and which are balanced in respect to the axis of the top. A counterpoise is attached to or may be made an integral part of each such rotatable member.

The inertia member attached to and revolving about the axial shaft serves as a medium for the transfer of energy from the relatively light motor, causes the top to rise from a reclining to vertical position, and serves as a stabilizer both in respect to the entire spinning cycle and the intermediate rhythmic undulations which produce the pleasing optical and tonal effects. The weight of this inertia element with its relatively heavy periphery may vary depending upon the effect which is to be produced, preferably being of the order of about one-half the total weight of the top.

The foregoing description has disclosed a further improvement in a novel combination of elements wherein the kinetic energy of the rotating counterpoises is utilized to vary the speed of the

shell of the top, the varying speed causing the production of undulated color and tonal effects.

I claim:

1. In a spinning top, the combination of (a) an outer shell consisting of upper and lower hollow cup shaped members, said shell members being secured together at their peripheral edges, (b) means within said outer shell for rotating said top, (c) rotatable members in a plane coincident with the axis of said top engaged with said rotating means and balanced in respect to the axis of said top, (d) a counterpoise near the periphery of each rotatable member, and (e) an inertia member engaged with said rotating means and rotatable about the axis of said top.

2. A spinning top, the combination of (a) an outer shell consisting of upper and lower hollow cup shaped members, said shell members being secured together at their peripheral edges, (b) pigmented areas on the exterior of said shell for producing undulating color changes during the spinning of said top, (c) means within said outer shell for rotating said top, (d) rotatable members in a plane coincident with the axis of said top engaged with said rotating means and balanced in respect to the axis of said top, (e) a counterpoise near the periphery of each rotatable member, and (f) an inertia member engaged with said rotating means and rotatable about the axis of said top.

3. In a spinning top, the combination of (a) an outer shell consisting of upper and lower hollow cup shaped members, said members being secured together at their peripheral edges, (b) means associated with said outer shell for producing undulating musical notes during the spinning of said top, (c) means within said outer shell for rotating said top, (d) rotatable members in a plane coincident with the axis of said top engaged with said rotating means and balanced in respect to the axis of said top, (e) a counterpoise near the periphery of each rotatable member, and (f) an inertia member engaged with said rotating means and rotatable about the axis of said top.

4. In a spinning top, the combination of (a) an outer shell consisting of upper and lower hollow cup shaped members, said members being secured together at their peripheral edges, (b) pigmented areas on the exterior of said shell for producing undulating color changes during the spinning of said top, (c) means associated with said outer shell for producing undulating musical notes during the spinning of said top, (d) means within said outer shell for rotating said top, (e) rotatable members in a plane coincident with the axis of said top engaged with said rotating means and balanced in respect to the axis of said top, (f) a counterpoise near the periphery of each rotatable member, and (g) an inertia member engaged with said rotating means and rotatable about the axis of said top.
